FENCE POST

Harold L. Craig, Hampton, Iowa

Application September 27, 1946, Serial No. 699,900

2 Claims. (Cl. 174—45)

1

My invention relates to improvements in fence posts for use with electrically charged wire fencing.

The primary object of the invention is to provide a durable, lightweight, strong, metal post equipped for easy driving into the ground by foot pressure, and embodying efficient, simply constructed means for fastening fence wire thereto and insulating the wire therefrom.

Other and subordinate objects, also comprehended by my invention, together with the precise nature of my improvements and the advantages thereof will be readily understood when the succeeding description and claims are read with reference to the drawing accompanying and forming part of this specification.

In said drawing:

Figure 1 is a view in side elevation of my improved fence post in a preferred embodiment thereof.

Figure 2 is a view in rear elevation.

Figure 3 is a view in side elevation of the combined fastener and insulator drawn to a larger scale and showing the same in fastening position.

Figure 4 is a similar view showing the fastener unfastened.

Figure 5 is a view in plan of the fastener and insulator and with the post shown in cross-section.

Figure 6 is a view in rear elevation of the presser plate.

Figure 7 is a view in side elevation drawn to a larger scale and illustrating the manner in which the driving device is operated.

Figure 8 is a view in vertical section taken on the line 8—8 of Figure 7.

Figure 9 is a fragmentary view in front elevation drawn to a larger scale and illustrating the anchor plate, and

Figure 10 is a view in vertical section taken on the line 10—10 of Figure 9.

Referring to the drawing by numerals, my improved fence post, as shown, comprises an elongated, narrow, channel iron member 1 with a bevelled lower end 2 for driving into the ground, and a longitudinal reinforcing rib 3 pressed into what constitutes the front 4 thereof and terminating short of the ends of said member for a purpose presently seen.

A rectangular anchor plate 5 is opposed to the front 4 of said member 1 at a suitable distance from the lower end 2 for imbedding in the ground 6 and which is fastened to said member 1 with corners thereof projecting beyond the sides 7 of said member 1 and by means of lugs 8 extended

through apertures 9 in said front 4 and bent down against said front.

A driving device, designated as a unit by the numeral 10 is provided above said anchor plate 5 for forcing said member 1 into the ground 6 by foot pressure. The driving device 10 comprises a clip-like slide 11 adapted to straddle the member 1 from the front 4 thereof and having side flanges 12 extending rearwardly beyond the sides of said member, and a right angled foot rest lever 13 pivoted intermediate its ends between the flanges 12 in the rear of the member 1 for vertical rocking movement on a pivot pin 14 removably extended through said flanges 12 and through said lever. The foot rest lever 13 is formed with a downturned inner end dog 15 on one side of the pivot pin 14 adapted to bear against the front 4 of the member 1 when pressure is exerted by the foot downwardly on said lever on the other side of said pivot pin 14, and whereby the front 4 of said member 1 is gripped between said slide 11 and the dog 15 so that such downward foot pressure will drive the member 1 into the ground 6. By swinging the foot lever 13 counterclockwise, as shown in dotted lines in Figure 7, the slide 11 may be freed for sliding upwardly or downwardly on said member 1, as the occasion may require. Normally, the foot rest lever 13 is overbalanced on the side of the pivot pin 10 opposite the dog 15 to engage said dog with the front 4 of said member 1 and thereby frictionally lock the slide 11 in selected position on said member. By removing the pivot pin 14, the driving device 10 may be disassembled and detached from the member 1 after said member has been driven into the ground.

A combined fastener and insulator 16 is provided on the upper portion of the member 1 and which includes a pair of front and rear insulation blocks 17, 18 having confronting faces 19, 20 provided with pairs of upper and lower complementary grooves 21, 22 of different depth in each pair and adapted to clamp fence wire 23 of different gauge therein, said blocks being adapted to be clamped to said member 1 in different vertical positions as the case may require. The block 17 is reduced, as at 24, to slidably fit in the channel of said member 1 for vertical adjustment therein while guided by said channel. For clamping the blocks 17, 18 together, and to said member 1, a rod-like, U-shaped, clamping bail 25 is provided to straddle said member 1 and said blocks 17, 18 with its bight spaced from the front 4 to said member 1. Side grooves 26 in said blocks 17, 18, in which the sides of the clamping bail

25 are fitted, prevent said bail and said blocks from slipping relatively, vertically. The clamping bail 25 is formed with ball-like free ends 27 for passing through and interlocking with key-hole slots 28 in opposite sides of a presser plate 29 opposed to the rear block 18 and adapted to be secured thereto by spring clips 30. A bail tightening bar with a hook camming end 31 and a straight handle 32 provides for camming the clamping bail 25 forwardly, the clamping end 31 being pivoted, as at 33, on the bight of said bail 25 to be rolled against the front 4 of said member 1 and extended upwardly through said bail when the handle 32 is swung downwardly and rearwardly into flat engagement with the front 4 of said member 1. As will be clear, when the clamping bail 25 is swung, as described, the camming end 31 co-acts with the front 4 of said member 1 to cam said clamping bail 25 forwardly and thereby urge the presser plate 29 forwardly against the clamping block 18 so that said blocks 17, 18 are clamped together and against the member 1. As will also be clear, when the bail tightening bar is swung, as described, said bar is maintained in position by being swung past a dead center position. When the bail tightening bar is swung away from the member 1, the presser plate 29 and the clamping blocks 17, 18 will become loose so that the combined fastener and insulator 16 may be set vertically into different positions and the clamping blocks 17, 18 separated sufficiently to permit fence wire to be introduced into the grooves 21, 22, selectively.

The foregoing will, it is believed, suffice to impart a clear understanding of my invention, without further explanation.

Manifestly, the invention, as described, is susceptible of modification without departing from the inventive concept, and right is herein reserved to such modifications as fall within the scope of the appended claims.

I claim:

1. A fence post comprising an elongated member, a pair of opposed insulated blocks adapted to be clamped against opposite sides of wire fencing, and means for clamping said blocks against said fencing and one block to said post comprising a presser plate opposed to the other block with key-hole slots therein, a bail straddling said member and blocks with enlarged ends interlocking with one end of the slots and removable out of the other ends of said slots, and a member on said bail swingable against said elongated member to exert pressure on said bail to pull said plate against said other block.
- 5 2. A fence post comprising an elongated member, a pair of opposed insulated blocks adapted to be clamped against opposite sides of wire fencing, and means for clamping said blocks against said fencing and one block to said post comprising a presser plate opposed to the other block, an endwise movable bail straddling said member and blocks and connected to said presser plate to cause the same to press against said other block upon movement of the bail endwise, and
- 10 20 25 a bar on said bail swingable thereon against said member to cam said bail endwise.

HAROLD L. CRAIG.
